UNITED STATES PATENT OFFICE.

RICHARD W. HOUSTON, OF BALTIMORE, MARYLAND.

BOTTLE-HOLDER.

932,128.

Specification of Letters Patent.

Patented Aug. 24, 1909.

Application filed August 17, 1908. Serial No. 448,820.

To all whom it may concern:

Be it known that I, RICHARD W. HOU-
TON, a citizen of the United States, residing
at Baltimore, in the State of Maryland, have
5 invented certain new and useful Improve-
ments in Bottle-Holders, of which the fol-
lowing is a specification.

This invention relates to an improved
bottle-holder.

10 The object of the invention is to provide
a holder for bottles that contain liquid food
so that the same may be administered to in-
fants, invalids and others who are unable to
help themselves, especially when in a recum-
15 bent position.

The invention is illustrated in the accom-
panying drawing in which,—

Figure 1 is a perspective view of the im-
proved bottle-holder as seen when attached
20 to the head of a child's bed. Fig. 2 is a de-
tail view in section on a larger scale, of the
clamp by which the holder may be attached
to the cross-rail of a bedstead. Fig. 3 is a
25 view showing broken parts of the bottle and
holder. Fig. 4 is a section view showing the
construction of pivoted automatic adjuster
which is attached to the clamp.

My bottle-holder comprises a device to
clip onto the bottle, a short length of non-
30 resilient flexible-arm, a pivoted shank which
carries the flexible-arm and has means for
automatically securing it in whatever posi-
tion it may be set, and a clamp by which
35 these last-named devices may be attached
to the rail of a bedstead or other structure.

The bottle-holder proper consists of a wire
having resilient qualities and suitably shaped
40 to form two clip or grip parts, 1, 2, adapted
to take hold of a bottle, 3. One clip part
comprises a hook, 1, adapted to take about
the neck of the bottle, which in the drawing
is shown with its neck pointing downward.
45 In this instance a rubber nipple, 4, is shown
on the neck of the bottle. The other clip
part may be in the form of a resilient loop,
2, adapted to press the bottom of the bottle;
the said two clip parts, 1, and, 2, are con-
50 nected by a straight bar, 5, which extends
parallel with respect to the length of the
bottle. The clip part, 2, that is in the form
of a loop may have a circular knob or disk,
6, as shown which will contact directly with
55 the bottom of the bottle. The two clips
will yield to permit the bottle, 3, to be pressed
into position between them and the bottle
will then be properly held. If desired the

spring-wire that forms the bottle-clips may
be covered by a sleeve or tube, 7, of rubber.

The clip loop, 2, has its end, 8, screw-
threaded to better attach it to one end, 9, of 60
the non-resilient flexible arm, 10. This
flexible arm is a well-known construction
used for other purposes, which will yield or
bend when strain is applied to it, but being
non-resilient will ordinarily retain its curved 65
form or position when it has been set. The
other end, 11, of the flexible arm has a stiff
rod or shank-arm, 12, which is pivoted or
jointed at, 13, to a clamp, 14, which may be
secured to any structure, such as the rail, 15, 70
of a bedstead. The clamp, 14, is shown in
Figs. 1 and 2; one side of the clamp is open
to admit of its being slipped on to the rail,
15, and one side has a thumb screw, 16,
whose end carries a pad, 17, so that when the 75
pad is forced against the wood rail, 15, the
latter will not be injured. The rod or
shank-arm, 12, being pivoted on a bolt or pin,
13, projects upward and will have a swinging
or hinged movement. 80

Means are employed to act automatically
and secure the pivoted shank-arm, 12, in any
position to which it may be set. This means
may comprise a ratchet-segment, 18, which
is fixed on the clamp device, 14. The teeth, 85
19, of this segment form a curve that is con-
centric with respect to the pivot-bolt or pin,
13, on which the shank-arm, 12, turns. It is
obvious that either one or two segments, 18,
may be used. In the present instance two 90
are shown, and the end of the shank-arm is
between the two. The shank-arm carries a
pawl, 20, that is normally pressed by a
spring, 21, so as to keep the pawl engaged
with the teeth of the segments. 95

It will be seen that the construction is such
that when a little force is applied to the
shank-arm the pawl will yield, and the
shank-arm will turn on its pivot, 13, and
that when the shank-arm has been set to the 100
approximate position desired the pawl and
teeth will retain it. The non-resilient flexi-
ble arm and the bottle holder carried thereby
may then be bent to the precise point de-
sired without further adjustment of the 105
shank-arm and as the flexible arm is non-
resilient and will not spring back, it will re-
tain the bottle-holder at the desired point.

* Having thus described my invention what
I claim and desire to secure by Letters Pat- 110
ent is,—

1. A bottle-holding device comprising a

screw clamp having a ratchet segment,—a stiff arm pivoted to the clamp and having a pawl to engage the ratchet segment; a bottle holder comprising a single piece of wire having a clip formed at one end and at its other end having a support for the bottom of the bottle and a non-resilient flexible arm having one end connected to the wire bottle holder and its other end connected to the 10 stiff pivoted arm.

2. A bottle holding device comprising a screw clamp having spaced-apart ratchet segments; an arm pivoted to the clamp be-

tween said ratchet segments; a pawl carried by said arm; a non-resilient flexible arm having one end connected to the pivoted arm, a wire bottle holder engaging and carried by the flexible arm,—said bottle holder having a loop at one end to engage the bottom of a bottle and a clip at the other end. 15 20

In testimony whereof I affix my signature in presence of two witnesses.

RICHARD W. HOUSTON.
